ROTARY KITE

Henry J. Martin, Saginaw, Mich.

Application August 17, 1953, Serial No. 26,490

Term of patent 7 years

(Cl. D34—15)

Fig. 1 is a front perspective view of a rotary kite, showing my new design; and,

Fig. 2 is a rear perspective view thereof.

The broken line showing of the string is for illustrative purposes only.

I claim:

The ornamental design for a rotary kite, as shown and described.
